DESIGN FOR A COMBINED PROPELLER SHAFT STRUT AND RUDDER SUPPORT

Andrew J. Higgins, New Orleans, La.

Application October 26, 1938, Serial No. 80,695

Term of patent 14 years

To all whom it may concern:

Be it known that I, Andrew J. Higgins, a citizen of the United States, residing at New Orleans, in the parish of Orleans and State of Louisiana, have invented a new, original, and ornamental Design for a Combined Propeller Shaft Strut and Rudder Support, of which the following is a specification, reference being had to the accompanying drawing, forming part thereof.

Figure 1 is a side elevational view of a com-

bined propeller shaft strut and rudder support, showing my new design;

Figure 2 is a perspective view;

Figure 3 is an enlarged cross section taken along the line 3—3 of Figure 1.

I claim:

The ornamental design for a combined propeller shaft strut and rudder support, as shown.

ANDREW J. HIGGINS.
